(57) **CLAIM**

The ornamental design for a bullet, as shown and described.

DESCRIPTION

FIG. 1 is a perspective view of a bullet, showing our new design;

FIG. 2 is another perspective view thereof, from a different angle than FIG. 1;

FIG. 3 is an end view thereof;

FIG. 4 is a side view thereof;

FIG. 5 is another side view thereof;

FIG. 6 is an end view thereof, opposite that of FIG. 3; and, FIG. 7 is an enlarged view of of FIG. 1.

The broken lines in the drawing depict portions of the bullet that form no part of the claimed design. The bold broken lines illustrate the extent of the enlarged view of the drawing and forms no part of the claimed design.
